UNITED STATES PATENT OFFICE.

GEORGE MCKEAN, OF CORTLAND, NEW YORK, ASSIGNOR OF ONE-HALF TO
E. D. BARKER AND A. L. CHAPLIN, BOTH OF SAME PLACE.

ADJUSTABLE BRACKET FOR CURTAINS.

SPECIFICATION forming part of Letters Patent No. 415,680, dated November 19, 1889.

Application filed June 26, 1889. Serial No. 315,574. (No model.)

To all whom it may concern:

Be it known that I, GEORGE MCKEAN, a citizen of the United States, residing at Cortland, in the county of Cortland and State of New York, have invented certain new and useful Improvements in Adjustable Brackets for Curtains; and I do hereby declare the following to be a full, clear, and exact description of the invention, such as will enable others skilled in the art to which it appertains to make and use the same, reference being had to the accompanying drawings, which form part of this specification.

My invention relates to adjustable brackets for window-curtains, and the object is to provide an adjustable bracket capable of being set by a sliding bar to suit curtains of varying width, and also to permit the curtain to be shifted laterally toward either side.

To these ends the invention consists in the construction and arrangement hereinafter described, and more particularly pointed out in the claim.

It is sometimes necessary or desirable to change a curtain from one window to another, and in such cases it is more convenient to change the roller with its curtain than to change the curtain from one roller to another. If, however, the bracket be permanently screwed or nailed to the window-frame, as in the case of the ordinary bracket, which is attached to the face of the window-frame, it will be necessary to move one or both brackets, if the roller be either longer or shorter than that for which they were set; or if they be set on the inside of the frame, as is often the case, it will be necessary to shorten the roller, if too long, or to substitute a new one if too short. In either case much time is consumed, and by moving and resetting the brackets the window-frame is marred and defaced. My adjustable bracket avoids these difficulties and disadvantages, and allows curtains to be easily and quickly changed from one window to another.

In the accompanying drawings, which illustrate my invention and form a part of this specification, Figure 1 is a perspective view of a pair of brackets in position on the window-frame and supporting between them a roller and curtain. Fig. 2 is a perspective

view of one of the brackets and its keeper or holder. Fig. 3 is a view of a rectangular bar with the bracket reversed on the frame, and Fig. 4 represents a horizontal section through one of the brackets and its keeper.

Like letters refer to corresponding parts in each figure of the drawings.

A designates a straight bar or rod with preferably a flatside, which is placed directly against the side of the casing C of the window-frame, for the purpose of slightly compressing the bar within the wood and securing a long bearing-surface for it, to prevent the usual rocking or oscillating movement of the bracket when the curtain-roll is operated upon brackets of this character. At one end of this rod or bar is a flat bracket-ear a, formed integral therewith, which stands out at right angles to the bar and forms the bracket proper. The ear is centrally perforated at c to receive and form a bearing for the journal of the roller E.

B designates an open-backed keeper which holds the bracket in position on the window-casing C. This keeper is closely fitted over the bar A and is provided at its two ends with perforated ears b, through which it is screwed against the casing. When the keeper is drawn down upon the casing by the screws D in its ends, the bar is slightly embedded in the wood and held tightly against the casing, preventing its movement in either direction. When it is desired to adjust the bar A, the holding-screws of the keeper are slightly loosened, when the bar is moved and the screws are reset. The brackets being in position on the window-casing, with the screws D partially inserted through the ears of the keepers, the roller E is placed between them, and the ears of the brackets are then moved toward each other until both journals of the roller enter the respective opening in the ears, when the bars A are fixed in position by tightly screwing the keepers down upon the casing.

Should it be desirable to shift the curtain laterally, the screws D are retracted and the two brackets and the roller moved together in the desired directions, and again secured by the screws when properly adjusted.

By making the sliding rod A and the bracket-

ear *a* integral these parts are always in proper relative position and there is no danger of their being separated and lost. Moreover, they are more easily and cheaply made 5 and more conveniently applied.

A further and important advantage of my invention is in forming the bar A rectangular in shape in cross-section, so that it may be turned or reversed in the keeper, bringing 10 the bracket-ears on the inner or window side of the case with the curtain near the glass, or allowing it to project from the side of the window-case facing the room. By this construction the bracket may be turned outward 15 or inward, so as to support the roller and curtain in front of the window-casing, or between the sides of the casing, as may be desired.

Having thus fully described my invention, what I claim as new, and desire to secure by 20 Letters Patent of the United States, is—

Adjustable curtain-brackets consisting of bars, each having at one end a perforated ear integral with and at right angles to the bar to hold the journal of the curtain-roller, said bars held directly against the side of the casing and slightly compressed within the wood of the window-frame by open-backed keepers closely fitting over the bars and secured to the casing, said brackets being adjustable to and from each other and adapted to be turned 25 to hold the curtain-roll on the inner or outer sides of the window-casings by loosening the keeper at one end, as set forth.

In testimony whereof I affix my signature in presence of two witnesses.

GEORGE MCKEAN.
